UNITED STATES PATENT OFFICE.

JACOB RIBAYSEN, OF CHICAGO, ILLINOIS.

LAMP SOCKET.

Original application filed August 18, 1924, Serial No. 732,706. Divided and this application filed April 30, 1925. Serial No. 26,969.

The invention relates to lamp sockets and is a division of the application filed August 18, 1924, Serial Number 732,706.

In accordance with the principal object 5 of the present invention, the lamp socket is so constructed that it has self contained means for adjustment whereby the socket may be adjusted throughout a wide range.

A further object consists in sectionalizing 10 the cover of the socket whereby the body of the socket may be brought out of alignment with the terminal cover portion and the body and lamp adjusted in accordance with requirement.

15 To the accomplishment of the objects stated and others that will become apparent upon perusal of the description of the invention, the latter comprises a means set forth in the specification, particularly pointed out in the claim forming a part thereof, and illustrated in the accompanying drawing, in which,

Figure 1, is an elevational view of the socket as applied to a wall bracket, the adjusted body shown in dotted lines,

Figure 2, is a front view of the cover of the lamp socket,

Figure 3 shows the sections of the cover separated and part of the cover in section,

30 Figure 4 is a perspective view of the lower part of the cover,

Figure 5 is a perspective view in section of the assembled cover.

Referring to the several views of the drawings, 35 10 generally designates a wall bracket to which a socket generally designated by 11 may be secured by means of a set screw 12. The socket comprises a body portion or shell 13 while the cover comprises a sectionalized

40 body 14, which includes upper portion 15 and a lower part 16, which are separate parts and are divided along a plane forming an angle of 45° with respect to the horizontal plane.

It is, of course, not necessary that the line 45 of division should form an angle of 45° to the horizontal plane, but any other angle may be preferred or resorted to in accordance with special requirements which are to be met.

The upper part 15 has a collar 17 and a 50 hollow portion 18 terminating in a slanting

plane 19 from which projects a ring 20. The lower portion 16 includes a circular flange 21 from which upstands a hollow body 22 terminating in a slanting face 23, parallel to the slanting face 19 of the upper member 15 and equipped with an aperture 24 for the insertion of the ring 20.

The slanting faces of the parts 15 and 16 are in contact one with the other, and constitute an oblique joint, whereby, when the part 16 is turned relatively to the part 15, said part 16 will have an orbital movement while turning on its axis. This orbital movement will, because of the close relationship of the parts 15 and 16, be restricted, 65 and may therefore take place without contact of the bulb of the lamp with an adjacent object, such as a lamp shade. The sectionalized body 14 is substantially a sphere which has a minimum linear dimension that 70 affords a short radius, whereby the orbital movement is further restricted.

In order to secure the parts 15 and 16 of the cover together, the ring 20 is inserted through the aperture 24 and is then headed over as shown in Figure 5, whereby the upper part 15 of the cover is rotatably secured to the lower part 16. Attention is called to the fact that if an adjustment is effected between the two parts of the cover, there is 80 a relative movement between the two parts which is simultaneously a rotary and vertical movement so that the lower part of the cover, for instance, upon rotation may be brought out of the alignment position shown 85 in Figures 1 or 5 to a position at right angles thereto, as shown in Figure 1 in dotted lines.

It is very desirable to permit the adjustment of the lower part of the cover and therewith of the shell 13 attached thereto, especially when the lamp carried by the socket is to be removed.

While the drawing discloses a preferred embodiment of the invention, numerous 95 changes and alterations may be made within the purview of the invention without departing therefrom.

I, therefore, do not limit myself to the details of construction and arrangement as 100

shown, but include all changes constituting departures within the scope of the invention, as set forth in the appended claim.

I claim:

- 5 An electric lamp socket of the standard type including, a body portion, and a cover therefor, the latter being made in parts and divided in an oblique plane, the wall of one

of said parts having an aperture, and the wall of the other of said parts having a ¹⁰ headed tubular projection extending through said aperture to hold the parts together but permitting rotary movement thereof.

In witness whereof I affix my signature.

JACOB RIBAYSEN.
